(57) **CLAIM**

The ornamental design for an eyewear, as shown and described.

DESCRIPTION

FIG. 1 is a top, front, right side perspective view of an eyewear showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot-dash broken lines in the figures represent boundaries of the claimed design and form no part of the claimed design. All other broken lines represent portions of the eyewear that form no part of the claimed design.

1 Claim, 5 Drawing Sheets

US D870,190 S
